UNITED STATES PATENT OFFICE.

JOHN M. LARSON, OF CHICAGO, ILLINOIS, ASSIGNOR TO NATIONAL REGULATOR COMPANY, OF CHICAGO, ILLINOIS, A CORPORATION OF ILLINOIS.

HUMIDITY-CONTROLLING APPARATUS.

1,153,234.

Specification of Letters Patent. Patented Sept. 14, 1915.

Application filed January 11, 1910. Serial No. 537,504.

To all whom it may concern:

Be it known that I, JOHN M. LARSON, a citizen of the United States, residing at Chicago, in the county of Cook and State of Illinois, have invented new and useful Improvements in Humidity-Controlling Apparatus, of which the following is a full, clear, concise, and exact description, reference being had to the accompanying drawings, forming a part of this specification.

This invention relates to improvements in means for regulating the amount of moisture discharged into the air of a habitable room or space.

In the accompanying drawings, in which I have shown a practical application of my invention, there is illustrated a combination and arrangement of apparatus in the use of which air is drawn into a ventilating duct from a suitable place, as, for instance some point exterior to the building, and is first passed over or through a heating apparatus, the latter being controlled by a thermostat of some suitable type, placed in the duct at a point beyond the heater so as to be affected by the warmed air. The air then passes along the duct and is finally delivered to the space which is to be heated and ventilated. At some convenient point, as in the duct, there is arranged suitable means for delivering into the duct, when required, a quantity of water vapor, which mingles with the air. Hygrostatic means, so located as to be influenced by the moisture in the air, measure the amount of humidity and control the action of the moisture-delivering means as required to maintain the air at the desired humidity point.

In the drawings, Figure 1 is a front view, principally in elevation, of the hygrostat or humidity-responsive device which controls the moisture increasing means, with the cover or protecting cap removed; Fig. 2 is a front elevational view of the hygrostat with the cover in place; Fig. 3 is a cross sectional view of the same, the section being taken on the line 4—4 of Fig. 3; Fig. 4 is a side elevational view of the lower portion of the hygrostat with the cover removed.

The hygrostat comprises a base member 34 which may be secured to the wall 35 of the room by means of screws 36 and 37. Extending upward from the base member 34 is a pillar 38, the lower end of which is screw threaded and screwed into a correspondingly

threaded depression in the top of the base member 34. A passage 39 extends upward through the base member and registers with a passage 40 which extends through the pillar 38 for a portion of its length and opens at the discharge port 41 at the tip of a laterally projecting nipple 42. A pipe leads to the passage 39 of the base member, the air which passes up through the pipe being thus permitted to discharge into the atmosphere at the port 41. A filter 43, consisting of a quantity of cotton, felt or the like is arranged in an enlargement of the passage in the base 34 to intercept dirt or such matter as loose particles of rust and prevent it from passing up through the passage 40 and obstructing the discharge port 41.

Extending upward from the pillar 38 is a rod 44 which forms a post supporting the hygrostatic element of the device and a valve actuated thereby. The valve 45 is hung, by means of a strip 46 of resilient metal, upon a block 47 which is secured upon the post 44. The resilient strip 46 has a slight tendency to move the valve 45 away from the port 41. The hygrostatic element comprises a strip of wood 48 cut so that the grain runs crosswise of the strip, and a strip of brass or other suitable metal 49 which extends along one side of the wood strip 48. Secured to the upper end of the strip 49 is a metal block 50 from which extends upward a thin metallic strip 51 by means of which the hygrostatic element is supported or hung in front of the valve 45 from a block 52 which is secured to and carried by the post 44. Upon the lower end of the strip 49 is secured a second metallic block 53. The strip 48 of wood is confined at its ends between the blocks 50 and 53, and any expansion of this strip lengthwise which is due to an increased amount of moisture will, by the strip bearing upon these end blocks, cause the metal strip 49 to be flexed so that its lower end moves toward the valve 41. The metal strip does not absorb moisture and therefore is not increased or decreased in length by changes in the amount of moisture in the surrounding air. It is however, lengthened or shortened by rise and fall of temperature, but as the wood strip 48 is likewise lengthened or shortened by temperature changes, little or no flexing of the hygrostatic element as a whole results merely from a rise in temperature.

The block 50 is formed with a rearwardly extending lug 54 upon which bears the point of an adjusting screw 55 which extends downward through the supporting block 52. 5 This adjusting screw carries a pointer 56 which moves over a scale marked upon the edge of a disk 57 secured by means of a screw 58 upon the upper end of the post 44. By turning the screw to the right the lug 45 is 10 pressed down and thus the lower end of the hygrostatic element is adjusted toward and away from the discharge port 41. Upon the lower end of the strip 49 is provided a rounded hump 58 which bears upon the 15 valve 45.

When the temperature of the surrounding air rises, the metal strip 49 and the wood strip 48 expand or lengthen together. The lengthening of these strips has no effect 20 upon the valve 41, as the rounded hump 58 merely slides down along the back of the valve 45. The device is thus seen to be not directly affected, so far as the regulation of the flow of air from the port 41 is concerned, by temperature changes. Such 25 changes indirectly affect the position of the valve, however, as will be pointed out. Changes in the amount of humidity in the surrounding medium alter the position of 30 the valve with respect to its seat and thus vary the amount of air which is permitted to flow from the port 41, because the wood strip 48 expands when the amount of moisture increases, while the metal strip 49 does 35 not expand.

In practical service it is desired that the relative humidity, rather than the absolute humidity of the atmosphere of the room or space, be maintained practically constant. 40 By relative humidity is meant the ratio between the total amount of humidity which air will carry without precipitation at the temperature existing in the room and the amount actually present. As is well understood, air at a given temperature will hold 45 in suspension a certain quantity of water vapor, but if the temperature be lowered, or if the quantity of moisture be increased, the air is not able to hold all of the vapor 50 in suspension and precipitation begins to take place. Instruments for indicating the condition of the air with respect to the amount of moisture carried thereby usually give the percentage of the total amount 55 which would be required to saturate the air at the existing temperature.

The hygrostatic element which I employ is capable of so governing the valve 45 as to maintain the relative humidity practically 60 constant. In order to effect this it must be able to increase the activity of the vaporizer when the temperature rises and to decrease it when the temperature falls for the reason that the dew point rises with the temperature. If such a degree of humidity is

to be maintained that the per cent. of saturation is constant it is evident that a rise in temperature should be accompanied by an increase in the amount of moisture in the atmosphere.

It has been customary to employ in apparatus of this class, for the hygrostatic element, a strip of hygroscopic material such as wood cut with the grain running crosswise, this strip being so employed as to 70 thrust endwise against a lever or other means for transmitting its motion to a valve. Such a strip of wood, employed in this way, is, upon a rise in temperature, subjected to 75 two influences working against each other. 80 The strip tends to lengthen because of the rise in temperature and it tends to shorten because of the fact that the air, being warmer, takes up a part of the moisture which was present in or upon the strip. On the other hand, if the temperature falls, the strip tends to shorten because of the change 85 in temperature but tends also to lengthen because of the fact that the air, being cooler, is more ready to part with its moisture and 90 a quantity is absorbed by the wood. These two opposing forces thus to a great extent 95 interfere with the efficiency of such devices.

In my improved hygrostat, if the temperature of the surrounding medium be lowered the effect upon the metal strip 49 will be to shorten the same. The effect upon the wood strip 48 is to lengthen the same, because the air is more ready to part with its moisture, 100 this lengthening being somewhat interfered with, however, by the property of wood of contracting upon a fall in temperature. The tendency of the wood to expand, combined with the tendency of the metal strip to contract, causes the hygrostatic element to flex, thus moving the valve toward its seat. The effect then, is for a fall in temperature to 105 close the valve just as would be the case were the vaporizer unduly active or were the air for any other reason to become too moist. Upon the temperature rising the strip of metal expands. The wood strip likewise tends to expand, but this tendency is not as great as its tendency to contract due to the 110 fact that the air now has an increased avidity for moisture and dries out the wood strip to a certain extent. The combined action of the metal strip and the wood strip are now to open the valve, as would be the 115 case were the air to become too dry.

If the valve for the port 41 were carried directly by the hygrostatic element it would not always seat properly as the angle between the axis of the port and the back of the metal strip 49 is not always the same. Moreover, the hygrostat as a whole 120 lengthens and shortens under temperature changes. As this occurs the rounded hump 58 simply slides along the back of the valve without affecting the latter in any way.

To protect the hygrostat and conceal the same a suitable cover or casing 59 is provided, this cover having a lug 61 at each of its ends by means of which it may be secured by suitable screws 62 or the like to the wall to which the hygrostat is secured. This cover is formed with a series of perforations 63 to permit the passage of air freely to the sensitive element, these openings being guarded by wire screens or the like 64 to prevent the insertion of pencils and the like by meddlesome persons.

Having thus described my invention, what I claim as new, and desire to secure by Letters Patent, is:

1. The combination of a base, a pillar extending therefrom, said base and pillar having a passage extending therethrough and terminating in a port at the side of the pillar, a valve hung in front of said port and supported by said pillar, and a hygrostatic element consisting of a strip of metal and a strip of hygroscopic material arranged parallel with each other, said element being supported at one end from said pillar, the other end of said element bearing upon said valve and moving toward said port when said element is flexed and having movement transversely of said port when elongated.

2. A hygrostat having a port, a valve supported in front of said port, a hygrostatic element arranged in front of said valve and supported at one of its ends so as to be capable of swinging, and means for angularly adjusting said end and thereby regulating the position of the opposite end of the element with respect to said valve.

3. The combination of a base, a pillar extending therefrom, said base and pillar hav-

ing a passage extending therethrough and terminating in a port at the side of the pillar, a valve hung in front of said port, and a hygrostatic element consisting of a strip of metal and a strip of hygroscopic material arranged parallel with each other, said element being supported at one end from said pillar, the other end of said element bearing upon said valve and moving toward said port when said element is flexed and having movement transversely of said port when elongated.

4. A hygrostat having a port, a valve supported in front of said port, a hygrostatic element arranged in front of said valve and supported at one of its ends so as to be capable of swinging, and means for regulating the position of the opposite end of the element with respect to said valve, said hygrostatic element consisting of a hygroscopic element and a non-hygroscopic element, each having the same co-efficient of expansion by temperature.

5. A hygrostat having a port, a valve supported in front of said port, a hygrostatic element arranged in front of said valve and so supported as to be capable of swinging, and means for regulating the position of the ends of said element with respect to said valve, said hygrostatic element consisting of a hygroscopic element and a non-hygroscopic element, each having the same co-efficient of expansion by temperature.

In witness whereof, I have hereunto subscribed my name in the presence of two witnesses.

JOHN M. LARSON.
